ATTORNEY

UNITED STATES PATENT OFFICE.

GEORGE W. BRYANT, OF NEW YORK, N. Y.

DESIGN FOR A MOURNING-FLAG.

52,468.

Specification for Design.

Patented Sept. 24, 1918.

Application filed May 24, 1918. Serial No. 236,430. Term of patent 14 years.

To all whom it may concern:

Be it known that I, GEORGE W. BRYANT, a citizen of the United States, residing at New York, in the county of New York and State of New York, have invented a new, original, and ornamental Design for Mourning-Flags, of which the following is a specification, reference being had to the accompanying drawing forming part thereof.

In the drawing the figure is a plan view of the mourning flag.

I claim:

The ornamental design for a mourning flag, as shown.

GEORGE W. BRYANT.

Witnesses:

SIEGFRIED JOSEPHY,
JAMES COLEMAN.
